FLOW INTERMITTER

Alexander Boynton, San Antonio, Tex.; Sida S. Martin executrix of said Alexander Boynton, deceased

Application September 29, 1941, Serial No. 412,869

10 Claims. (Cl. 103—245)

My invention relates to flow intermitters for cased wells, and deals with the general subject matter of my Patents No. 2,262,750, issued November 18, 1941, and No. 2,263,565, issued November 25, 1941.

The principal object is to provide automatic means for causing a well to flow at predetermined intervals and during predetermined lengths of time.

Another object is to provide means for such purpose which will apply pressure fluid force to the producing formation only while the well is flowing, the pressure being withdrawn from the producing formation while the well is building up each head of liquid.

A further object is to control the duration of the flowing operation and the interval between such operations by means independent of gas pressure within the well.

Another object is to enable a well to be flowed at predetermined intervals and during predetermined lengths of time without subjecting the producing formation of the well to any pressure from the air or gas employed to lift the well liquid, this result being accomplished by employing a packer or string of pressure tubing surrounding the flow tubing, the annular space between the two strings of tubing being closed hermetically proximate their extreme ends.

A still further object is to provide a flow intermitter which will cause flow devices to operate more efficiently and without manual control at pressures which may be varied by adjusting the intermitter.

In addition to the foregoing, another object is to cut off the supply of pressure fluid and thereby prevent waste thereof whenever the accumulated well fluid has been expelled, if that should occur before the expiration of the predetermined flowing period.

Another object is to provide an intermitter which may be operated by pressure fluid ranging in value from only slightly above the atmosphere to that of the pressure fluid employed by it in flowing wells.

A further object is to conserve natural gas and lengthen the natural flowing life of oil wells by closing the wells in before or when their gas begins to break through the well liquid and by opening the wells again when they have built up enough gas to flow them.

Another object is to record the number of flowing operations during known intervals.

In accomplishing the foregoing objects by means of the preferred construction, I employ a

5 piston assembly within two aligned cylinders, each one of the cylinders being connected with a source of compressed air or gas. The pressure is reduced alternately in one of the cylinders and then in the other cylinder by bleeding off the pressure fluid, thereby causing the piston assembly operative within the cylinders to move alternately in opposite directions and to actuate a plurality of valves which control the intermittent flowing operations to accomplish the stated objects.

In the modified form, a pressure regulator controls the low pressure in one of the cylinders, while a bleeder valve is employed to deplete the 15 pressure in the other cylinder until it become less than that within the low pressure cylinder. The resulting intermittent difference in pressures obtaining in the cylinders containing opposite ends of the piston assembly causes the piston assembly to travel first in one direction and then in the other; thereby operating a plurality of valves to accomplish the foregoing objects.

A latch retards the movement of the piston assembly in both directions in order that any movement begun will be completed with certainty.

The piston assembly is adapted to operate six valves in the preferred embodiment and four valves in the modified construction. These valves control the duration of the flowing period, the 20 intervals between such periods, the admission of pressure fluid into the well, and the withdrawal of pressure fluid from the well.

A mechanical counter is actuated by the piston assembly to record the number of flowing operations, all of which will become more apparent from an examination of the following specification and accompanying drawings, in which—

Fig. 1 is a front elevation of the preferred construction.

40 Fig. 2 is a continuation of the lubricator reservoir and connected conduit displaced from the left end of the intermitter assembly.

Fig. 3 is a continuation of similar parts to those shown in Fig. 2 displaced from the right end of the intermitter assembly.

Fig. 4 is a top view of the preferred construction.

Fig. 5 is a perspective view of the valve platform.

50 Fig. 6 is a top view of the platform and valves mounted on it in Fig. 1.

Fig. 7 is a typical horizontal section through the piston, cylinder, and latch of both constructions.

55 Fig. 8 is a perspective view of the cylinder

spacer member partially broken away to show a portion of the piston and connected drive pins.

Fig. 9 is a vertical section on the line 9—9, Fig. 7.

Fig. 10 is a top view of the modified construction.

Fig. 11 is a front elevation of the modified construction with both cylinders and the cylinder spacer member in vertical section showing the piston in partial vertical section.

Fig. 12 is an outside view of a portion of the oil reservoir and piping displaced from the left end of Fig. 11.

Fig. 13 is an outside view of a portion of the oil reservoir and piping displaced from the right end of Fig. 11.

Fig. 14 is a top view of the platform and valves mounted upon it as employed in the modified construction.

Similar characters of reference are employed to designate similar parts throughout the several views.

The casing head 3 is employed to form a hermetic seal between the well casing 1 and the flow tubing 2, proximately above the ground surface 4, the tubing being positioned centrally within the casing and surrounded by the annular space 1a.

A flow line connection or tubing extension nipple 5, which may be of the same diameter as the tubing 2 is shown connected to the tubing by the union 2a which is employed for convenience in assembling the intermitter and removing it from the well. The nipple 5 may be bent as shown and joined to an unshown flow line leading to a production tank. Manifestly this nipple may be considered as an outward extension of the tubing or as an extension of said flow line joined to the tubing.

The cylindrical assembly consisting of the cylinder spacer member 6, having the external longitudinal reinforcing ribs 6m and the cylinders 7 and 8, is secured upon the nipple 5 by the upper clamp bolts 40, Figs. 1 and 4, and 41, Fig. 7, which bolts are received through openings in the tubing clamps 38 and 39.

The bevels of the nuts 43 are received within corresponding countersinks in the clamps, (see Fig. 9) in order securely and adjustably to position the bolts centrally within the openings through the clamps. The similar nuts 42 of the bolts 40 are engaged similarly upon the clamps.

The two clamp bolts 41 are engaged threadedly within the bosses 6d and 6e of the cylinder spacer member 6, Figs. 7 and 9, while the two bolts 40 are received through openings in the supporting flange 6c to which flange these bolts are locked by the nuts 42. The heads of the bolts 40 and the nuts 42 are beveled like the nuts 43 in Fig. 9, these beveled surfaces being received within conforming countersinks within the supporting flange 6c of the cylinder spacer member 6 for the purpose of rigidly securing the bolts 40 centrally within the openings through the flange.

The cylinders 7 and 8 are aligned with the spacer member 6. The right end cylinder 7 has its flange 7a secured to the flange 6a of the spacer member by the bolts 9, and the left end cylinder 8 has its flange 8a secured to the flange 6b of the member 6 by the bolts 10.

The piston member 11 (see Fig. 7) has at one end the piston head 11b, closely slideable within the cylinder 7, and has at its other end the piston head 11c, closely slideable within the cylinder 8.

The right end piston head 11b has an extension 11d, and the piston head 11c has a similar extension 11e. The U cups or other form of packing 12 and 13 and the spacer rings 14 and 15 separating these cups, each has a central opening which closely receives the extensions 11d and 11e, respectively.

The dashpot plunger 16 has threaded connection with the extension 11d and serves to lock the U cups 12 and the spacer ring 14 together and to hold them assembled against the end of the piston head 11b. Likewise, the U cups 13 and the spacer ring 15 are held assembled against the end of the piston head 11c by the dashpot plunger 17. The U cups 12, closely slideable within the cylinder 7, face the outer end of that cylinder, and the U cups 13, closely slideable within the cylinder 8, face in the opposite direction.

The cylinder 7 has an end extension forming the dashpot pocket 7b. The cylinder 8 has a similar end extension forming the dashpot pocket 8b.

The dashpot plunger 16 is tapered slightly, as appears in Fig. 7, and has very slight minimum clearance, such as one-sixty-fourth inch, within the dashpot pocket 7b whenever it engages therein at the end of the piston travel in that direction. Likewise, the dashpot plunger 17 is tapered slightly also and has similar clearance within the dashpot pocket 8b whenever it engages therein at the end of the piston travel in the opposite direction.

The latch, shown sectionized in Fig. 7, is for the purpose of delaying the movements of the piston assembly until sufficient energy is exerted upon either end thereof to complete the piston travel in the opposite direction. This latch is similar in operation to that disclosed in my co-pending application, Serial Number 267,193, filed April 10, 1939.

The latch shell 18 is secured against the cylinder spacer member 6 by the clamps 29 and 30, engaged with the bosses 6f and 6g, respectively, of the member 6 by the cap screws 31 and 32, respectively. The ends of the shell 18 are closed hermetically by the caps 19 and 20 engaging upon the packings 25a.

Proximate its ends, the latch shaft 21 has the latching recess 21a adapted to be engaged by the latch balls 22. The ball riders 23 urge the latch balls inwardly against the latch shaft and against the ball floors 24 by force of the coiled springs 27, both ball riders and springs having some clearance within the shell 18. Each of the ball floors 24 may be placed in proper position by being engaged threadedly with the shell and secured in proper position by the lock rings 24a. Each gland 26 may have threaded connection within one of the spring bases 28 in order properly to compress the packings 25. The latch may be engaged to the maximum depth of the recesses 21a at either end of the shaft 21 as shown, or the force of this engagement may be made less, as required, by screwing the members 24 and 24a farther outward, in order that the latch balls will engage less deeply within the recesses 21a. It will be understood that the parts 22, 23, 24, 24a, 25, 26, 27, and 28 are duplicated at each end of the latch assembly, and that the latch shaft 21, formed the same at both ends, engages with the latch balls in the same manner at each end, although the force of this engagement may be varied at either or both ends by adjusting the

position of the members 24 and 24a, as above stated.

The latch is operated by the movements of the piston member 11, the latch driver pin 33 being secured at one end within the enlargement 11g of the piston member, as appears in Fig. 7 and having its outer portion of reduced diameter engaged within the central opening through the latch shaft. The slot 18a of the shell 18 and slot 6k of the cylinder spacer member 6 register and are of such width and length that the pin 33 may slide freely therein during the piston movements. The latch balls 22 engage within the recess 21a of the latch shaft 21 at each end of the piston travel.

One end of the latch lubricator pipe 34, Figs. 1 and 4, is secured upon the shell 18 by the weld 34a and the other end is secured similarly by a similar weld. By removing the plug 35, the latch may be filled with a lubricant which will be confined by the packings 25, the latch shaft 21 remaining engaged with this packing during all movements of the latch.

Obviously the latch may be omitted and the variable force required to overcome frictional resistance of the parts at rest and in motion may be relied upon to replace the latch.

The mechanical counter 36, many types of which are available, may be secured upon the boss 6h of the cylinder spacer member 6 by the cap screws 37 (see Figs. 1, 4, and 8), where it will be actuated to count the well flowing operations by impact of the extension 33a of the latch driver pin 33, slideable within the slot 18b of the latch shell 18.

Proximately beneath the cylinder spacer member 6, the platform 44 is secured upon the nipple 5 by means of the bolts 46 engaging through the clamp 45 (see Fig. 6) and the clamp portion 44a of the platform member 44 (see Fig. 1). This platform shown separately in Fig. 5, has the slots 44b properly positioned to receive the several strap bolts, having their nuts engaged against the nether side of the platform for the purpose of securing the several valves shown mounted upon it (see Figs. 1 and 6).

The six valves securely mounted upon the platform 44 may be of the ordinary lubricated plug valve type, as shown. These valves are opened simultaneously by 90 degrees clockwise rotation of their operating levers and are closed simultaneously by a reciprocating movement which may be evenly divided on either side of a line projected longitudinally through the center of the valves. The valves are staggered as shown in Fig. 6, three of them facing in one direction and the other three facing in the opposite direction. This arrangement provides that three of the valves will be opening while the other three will be closing, if installed as usually manufactured, without the necessity of reversing their ports.

The larger high pressure casing input valve 47 and the casing bleeder valve 52 are secured upon the platform 44 by the strap bolts 53 and 58, respectively. The four smaller inner valves 48, 49, 50, and 51 are supported by bases which raise the smaller valves so that all valves will have their operating shanks on the same horizontal plane. The first feeder valve 48 and its base 59 are secured upon the platform 44 by the strap bolts 54. The first bleeder valve 49 and its base 59' are secured upon the platform by the strap bolts 55. The second bleeder valve 50 and its base 60 are secured upon the platform by the

strap bolts 56. The second feeder valve 51 and its base 60' are secured upon the platform by the strap bolts 57.

The operating lever 61, pressed over or otherwise secured upon the operating shank 47a of the valve 47, has the slot 61a which slidably receives the drive pin 67. The operating lever 62, pressed over the operating shank 48a of the valve 48, has the slot 62a which slidably receives the drive pin 68. The operating lever 63, pressed over the operating shank 49a of the valve 49, has the slot 63a which slidably receives the drive pin 69. The operating lever 64, pressed over the operating shank 50a of the valve 50, has the slot 64a which slidably receives the drive pin 70. The operating lever 65, pressed over the operating shank 51a of the valve 51, has the slot 65a which slidably receives the drive pin 71. The operating lever 66, pressed over the operating shank 52a of the valve 52, has the slot 66a which slidably receives the drive pin 72.

The slots 61a, 62a, 63a, 64a, 65a, and 66a are of proper length to allow for proper swing of the levers to open and close the valves.

It will be noted that the slots 44b of the platform 44, Fig. 5, are of such length that the position of the valves secured upon the platform may be adjusted so that the operating levers will impart the proper movement to open and close the valves.

The drive pins 67, 68, 69, 70, 71, and 72, which may be of equal diameters and lengths, are each secured within the enlargement 11f of one of the ribs 11a of the piston member 11 (see Fig. 8), and are at such distance apart that the levers 61, 63, and 65 will be parallel with each other and that the levers 62, 64, and 66 will be also parallel with each other. The slot 6j of the member 6 (see Fig. 11) is of such width and length that the drive pins 67 to 72, both inclusive, are slideable freely therein during the full length of the piston stroke in both directions.

The reason why three valves in one row will be set to open while the three valves in the other row close, will appear from the functions of these valves and of the conduits into which they are connected.

The compressed air or gas line 73 has connected into it the valve 73a, and the T's 73b, 74, 75, 76, and 104 and terminates at the check valve 77 with which it has connection.

Manifestly the pressure supply line 73 can be closed by the valve 73a and have communication with annular space 1a as a source of pressure fluid. To form this connection the plug 3b may be removed from the boss 3a of the casing head and the plug 73c may be removed from the T 73b and a conduit provided between said boss and T.

The emergency pressure relief conduit 78 has one end connected into the check valve 77 and the other end connected into the T 81.

The first conduit 80, having connected into it the T's 81, 82, 83, and 84, has one end connected with the first receiver 79 and the other end connected with the right side lubricator reservoir 100.

The casing feeder conduit 89, connected with the T 76, has connection with both ends of the valve 47 from which valve it doubles backward and is connected into the casing head 3; thereby having communication with the annular space 1a.

The first feeder conduit 85, connected into the T 75, has connection with both ends of the valve 48 and with the T 83, the first charger timing

valve 86 which may be a needle valve being connected into this line between the T 83 and the valve 48.

The second conduit 90, connected into the T 74, has connection with both ends of the valve 51 and with the T 97, the second charger timing valve 91, which may be a needle valve, being connected into this conduit between the T 97 and the valve 51.

The second conduit 94, having the T's 96, 97, and 98 connected into it, has one end connected into the second receiver 95 and the other end connected into the left side lubricator reservoir 101.

The first bleeder conduit 87, having the first bleeder timing valve 88, which may be a needle valve, connected into it, has connection with the T 82 and both ends of the valve 49 discharging to atmosphere, as appears in Fig. 6.

The second bleeder conduit 92, having the second bleeder timing valve 93 connected into it, has connection with the T 96 and both ends of the valve 50 discharging to atmosphere, as appears in Fig. 6.

The casing bleeder conduit 99, connected into the casing head 3 and thereby having communication with the annular space 1a, has connection with both ends of the valve 52 and discharges to atmosphere, as appears in Fig. 6, or may have its discharge end connected into a gas fuel line, or the like.

The initial equalizing conduit 106, having connected into it the T 109 and the valves 107 and 108, has connection at one end with the second receiver 95 and at the other end has connection with the first receiver 79.

The valves 107 and 108 will be considered as closed until otherwise specified.

The nipple 105 has connection with the T 104 of the pressure supply line 73 and also has connection with the T 109.

The oil reservoir 100, having within it the perforated baffle tube 100a secured to it by the weld 100b, and the similar reservoir 101 having within it the perforated baffle tube 101a secured to it by the weld 101b, may be filled with oil which will follow the piston assembly and lubricate the cylinders. The reservoir 100 is connected into the boss 7c of the cylinder 7, and the reservoir 101 is connected into the boss 8c of the cylinder 8. These oil reservoirs may be filled by removing the pressure gauges 102 and 103 or the bushings into which they are shown connected. The plug 7e, engaged within the boss 7d of the cylinder 7, and the plug 8e, engaged within the other similar boss 8d of the cylinder 8, provides means for draining the cylinders.

The first charger timing valve 86 controls the time required to build up pressure within the receiver 79, and the second charger timing valve 91 controls the time required to build up pressure within the receiver 95. These valves regulate the interval between flowing operations, as will appear later.

The first bleeder timing valve 88 controls the time required to bleed off pressure from the receiver 79, and the second bleeder timing valve 93 controls the time required to bleed off pressure from the receiver 95. These valves regulate the duration of the flowing operations, as also will appear later.

In operation of the intermitter illustrated in Figs. 1 to 9, both inclusive, compressed air or gas of proper value to flow the well will be supplied through the line 73. In the beginning, it will

be assumed that the piston assembly is at the extreme left as shown in Fig. 7. The valve operating levers then are in the position shown in Figs. 1 and 6. The valves 47, 49, and 51 are open, and the valves 48, 50, and 52 are closed. This begins the flowing operation in the following manner:

The open valve 47 is discharging pressure fluid into the annular space 1a through the conduit 89, this fluid being of proper value to flow the well. At the same time, the valve 52 is closed in order to prevent the pressure fluid from escaping out of the well through the conduit 99. The open valve 49 is draining pressure fluid to atmosphere out of the receiver 79 through the first bleeder timing valve 88 which valve is so adjusted as to reduce the pressure slowly in the receiver 79. At the same time, the open valve 51 is discharging pressure fluid into the receiver 95 through the second charger timing valve 91 which valve is adjusted so as to build up pressure slowly within the receiver 95. The valve 48 is closed so that it will not allow pressure fluid to enter the receiver 79 while the valve 49 is discharging pressure fluid out of it. At the same time, the valve 50 is closed so that it will not discharge pressure fluid out of the receiver 95 while the valve 51 is discharging into it.

The piston assembly being at the extreme left as in Fig. 7, and pressure fluid force being built up within the receiver 95 while similar force is being depleted within the receiver 79, it is apparent that the piston assembly will travel to the extreme right whenever the difference in pressures within these receivers is sufficient to cause the latch to be sprung.

When the piston assembly is at the extreme right, opposite from its position shown in Fig. 7, the valves 47, 49, and 51 will be closed and the valves 48, 50, and 52 will be open. This terminates the flowing operation in the following manner:

The valve 47 cuts off the entrance of pressure fluid into the well through the conduit 89, while the valve 52 discharges to atmosphere through the conduit 99 all pressure fluid remaining in the annular space 1a. The bleeder valve 49 is closed in order to allow pressure to build up within the receiver 79 through the open valve 48. At the same time, the valve 51 is closed in order to allow the open bleeder valve 50 to reduce the pressure within the receiver 95.

The piston assembly being at the extreme right, it is obvious that with pressure building up within the receiver 79 and being depleted within the receiver 95, the piston assembly will return to the left whenever the difference in pressures is such as will cause the latch to be sprung.

The latch, for example, may be adjusted to spring at ten or twenty pounds difference in the pressures obtaining within the receivers 79 and 95, provided these receivers are of such capacity that the piston displacement will cause somewhat less than ten or twenty pounds difference in these pressures, as the case may be.

The adjustment of the first bleeder timing valve 88 which bleeds pressure fluid out of the receiver 79 and the adjustment of the second charger timing valve 91, which governs the flow of pressure fluid into the receiver 95, determine the duration of the flowing operations.

The adjustment of the first charger timing valve 86 which controls the inflow of pressure fluid to the receiver 79 and the second bleeder timing valve 93 which controls the discharge of pres-

sure fluid to atmosphere out of the receiver 95, determine the intervals between flowing operations.

For purposes of this subsequent discussion, it is assumed that twenty pounds difference in the pressures within the receivers 79 and 95 will be sufficient to spring the latch at either end and to cause the piston assembly to complete its travel in either direction. Then if it be desired, for example, to flow the well for one hour each time, this may be accomplished by slightly opening the first bleeder timing valve 88 so that it will deplete twenty pounds of pressure out of the receiver 79 during one hour, and by slightly opening the second charger timing valve 91 so that it will permit the pressure within the receiver 95 to build up twenty pounds during one hour. Proper adjustment of the valves 88 and 91, of course, will provide any other desired flowing time.

If it be desired that the intervals between flowing operations be two hours, for example, this may be accomplished by adjusting the first charger timing valve 86 so as to allow twenty pounds of pressure to build up within the receiver 79 during two hours while the second bleeder timing valve 93 is adjusted to allow twenty pounds of pressure to be depleted out of the receiver 95 during two hours. Any other desired interval between flowing operations may be obtained by making proper adjustments of the valves 86 and 93, as is apparent.

In beginning the operation of this intermitter, the valves 107 and 108 may be left closed if it be desired to use low pressures to actuate the piston assembly. In such case, the operating pressures will vary alternately from zero to twenty pounds in opposite ends of the cylinders because when the device is first installed with the piston assembly positioned as in Fig. 7 there is no pressure in either end of the cylinders and the valve 51, placing pressure in the cylinder 8, is open, while the valve 49, bleeding pressure from the cylinder 7, is open also. This practice is to be preferred if the well will not "pump off" during the flowing operations.

If the well will pump off during the flowing operations, or is apt to do so, preferably the same pressure employed within the annular space 1a to flow the well should be employed also within the cylinders to operate the piston assembly. This is so, because the intermitter is made to terminate automatically the flowing operation whenever the gas blows through from bottom when the well cleans itself if the same pressure is employed to operate the cylinders as that employed to flow the well. This is accomplished by means of the check valve 71.

In employing the same pressure to operate the cylinders as that employed to flow the well, begin using the intermitter by first opening the valves 107 and 108 simultaneously. Pressure fluid then will enter and equalize within the receivers 79 and 95 through the conduit 106 leading out of the supply line 73. The bleeder valve 49, being then open and depleting pressure within the receiver 79 while the feeder valve 51 discharging pressure fluid into the receiver 95 is open also, it is evident that the same pressure as that obtaining within the line 73 will be employed then to operate the piston assembly, as will be understood from previous description of this mechanism.

Whenever the weight of the well liquid within the eduction tubing 2 becomes less than the force

of the pressure fluid employed to flow the well, the contents of the tubing will be expelled as a slug. As the upper end of this slug passes out through the flow line 5, the portion of the slug 5 still remaining in the tubing 2 will move faster and faster as more of the slug is expelled, with the result that pressure fluid will be withdrawn rapidly from the annular space 1a. This causes the pressure within the pressure supply line 73 10 to drop sharply then, resulting in the opening of the check valve 71 which then discharges pressure fluid out of the receiver 79 into the line 73. When pressure within the receiver 79 drops slightly from the loss of pressure fluid through 15 the check valve 71, the piston assembly will move to the right, thereby terminating the flowing operation, as hereinbefore explained.

Attention is directed to the fact that when the well cleans itself as stated in the preceding paragraph, the bleeder valve 49 has been reducing the pressure within the receiver 79 since the flowing operation began and that, consequently, the check valve 71 will be required to reduce this pressure only slightly more in order to terminate 20 the flowing operation. In practice, this is accomplished before the slug is expelled completely or almost instantly afterward, because the operator will adjust the flowing time so that a blow through from the bottom, ordinarily will not occur, but 25 if it does occur, this will happen usually when only one or two pounds less pressure within the receiver 79 will result in terminating the flowing operation.

If the valve 73a be opened just far enough to 30 admit into the line 73 only enough gas to flow the well, then when the well blows through from bottom the pressure in the annular space 1a will decrease rapidly.

The fact that the check valve 71 automatically 40 will reduce pressure within the receiver 79 whenever a well cleans itself, and thereby terminate the flowing operation, is one of the important features of this invention, for without such emergency provision gas from the supply line 73 45 would waste through the well until the bleeder valve 48 completed the necessary reduction of pressure within the receiver 79 to terminate the flowing operation in the usual manner.

If any pressure intermediate of the assumed 50 minimum pressure of twenty pounds and that employed to flow the well be desired to operate the piston assembly, that purpose can be accomplished by connecting a pressure regulator into the short nipple 105 between the line 73 and the 55 equalizing conduit 106.

In the modified construction illustrated in Figs. 10, 11, and 14, it will be understood that parts bearing the same reference characters as in the preceding embodiment are similar in form 60 and purpose in both constructions. The piston assembly, cylinder assembly, latch assembly, and the clamps and bolts securing them to the cylinder spacer member being the same in both constructions, these members will not be discussed 65 further.

This modified construction employs four valves mounted on a different platform from that shown in the preferred embodiment in combination with a pressure regulator and a somewhat 70 different system of piping to accomplish the same results as those hereinbefore described for the preceding construction.

The high pressure casing input valve 113, the high pressure bleeder valve 114, the high pressure feeder valve 115, and the casing bleeder

valve 116 are shown to be of the ordinary lubricated plug valve type, similar to the valves mounted upon the platform 44 in Fig. 6.

The pressure regulator 135 may be similar to the one disclosed in Patent Number 2,007,363, application for which patent was made by me, or this regulator may be of any other suitable type.

The platform 110 has mounted upon it the valves 113, 114, 115, and 116 operated by the levers 123, 124, 125, and 126, respectively, the levers being actuated by the drive pins 127, 128, 129, and 130, secured within the piston member 11. This construction, being somewhat similar to that previously described, will be discussed briefly.

The platform 110 has the slots 110b similar to the slots 44b of the platform 44 shown in Fig. 5 by means of which slots and the strap bolts 117, 118, 119, and 120, the valves 113, 114, 115, and 116, are secured to the platform, having the clamp-like extension 110a. The platform 110 is secured upon the nipple 5 by the bolts 112 engaging through openings in the clamp portion 110a of the member 110 and the clamp 111 (see Fig. 14).

In Figs. 11 and 14, it will be observed that the valve 113 is secured upon the platform 110 by the strap bolts 117. The valve 114, having under it the separate base 121, is secured upon the platform by the strap bolts 118. The valve 115, having under it the separate base 122, is secured upon the platform by the strap bolts 119. The valve 116 is secured upon the platform by the strap bolts 120.

The slots 110b of the platform 110 are of such length that the valves and the strap bolts securing the valves upon this platform may be positioned so that the operating levers will impart proper movement to open and close the valves.

The smaller valves 114 and 115 are raised by their respective bases 121 and 122, Fig. 11, until the operating levers of all four valves are on the same plane.

The lever 123, passed over or otherwise secured upon the operating shank 113a of the valve 113, has the slot 123a within which the drive pin 127 is slidable. The lever 124, secured upon the operating shank 114a of the valve 114, has the slot 124a within which the drive pin 128 is slidable. The lever 125, secured upon the operating shank 115a of the valve 115, has the slot 125a within which the drive pin 129 is slidable. The lever 126, secured upon the operating shank 116a of the valve 116, has the slot 126a within which the drive pin 130 is slidable.

The slots 123a, 124a, 125a, and 126a are of proper length to allow sufficient swing of the levers to open and close the valves which are adapted to be opened or closed by approximately 90 degrees turn of the levers secured upon their respective operating shanks.

The four drive pins, 127, 128, 129, and 130, similar to the six drive pins shown in Figs. 6 and 8, are secured within the piston member 11, Fig. 11, at such distance apart that the levers of the four valves will be parallel with each other. The slot 63, Fig. 11, is of such width and length that the drive pins 127, 128, 129, and 130 are slidable freely therein during the piston strokes.

Two of the valves mounted on the platform 110 open, while the other two valves close. Plug valves, such as shown secured upon the platform 110, ordinarily are manufactured to open by a clockwise turn of their operating shanks, but this action may be reversed by turning the stop

plates 90 degrees. In Figs. 11 and 14, the valves 113 and 115 have their stop plates turned 90 degrees in order that these valves will be opened by a clockwise turn of their operating levers 123 and 125, respectively, while the valves 114 and 116 are installed as usually manufactured, so that their operating levers will be moved clockwise to close these valves. Therefore, in Figs. 11 and 14, the valves 113 and 115 are open and the valves 114 and 116 are closed.

The high pressure compressed air or gas supply line 131 has connected into it the T's 132, 133, 134, and the valve 113, from the discharge end of which valve this line doubles backward and is connected into the casing head 3, by means of which connection the line 131 is placed in communication with the annular space 1a.

The low pressure cylinder conduit 136, having connected into it the pressure regulator 135, the check valve 137, and the T's 138, 139, 140, and 141, originates in its connection with the T 133 and terminates in its connection with the lubricator reservoir 100. This reservoir, in turn, is connected into the boss 7c of the cylinder 7 and has within it the baffle tube 100a secured to it by the weld 100b. The low pressure receiver 143 is connected to the low pressure cylinder conduit 136 by means of the nipple 155 having connection with this receiver and the T 139.

The emergency pressure relief conduit 144, having connected into it the check valve 145 adapted to open in the direction of the line 131 and to close in the direction of the conduit 136, has connection with the T's 134 and 138.

The high pressure feeder conduit 146 originates at its connection with the T 132 and has connection with both ends of the valve 115. This conduit terminates at its connection with the T 151 and has connected into it the charger valve 147.

The high pressure cylinder conduit 149, having connected into it the T's 150, 151, and 152, has connection with the high pressure receiver 148 and with the lubricator reservoir 101, which, in turn, has connection with the boss 8c of the cylinder 8, both oil reservoirs being of similar construction in both forms of the invention.

The high pressure bleeder conduit 153, having connected into it the bleeder timing valve 154, has connection with the T 150 and extends to the valve 114 with both ends of which valve it has connection and near to it discharges to atmosphere, as appears in Fig. 14.

The casing bleeder conduit 156 has connection with both ends of the valve 116 and with the casing head 3. This conduit is adapted to discharge pressure fluid out of the annular space 1a to atmosphere through its open end, as appears in Fig. 14.

It is assumed that ten pounds per square inch difference in pressures acting upon each end of the piston assembly will drive it for its full travel in the opposite direction.

In operation, after being installed upon a well as shown in Fig. 11, compressed air or gas of proper value to flow the well is assumed to be available in the line 131. The value of this pressure fluid, for example, will be assumed to be 200 pounds per square inch. It will be assumed further that the pressure regulator indicated at 135 is set to reduce the pressure of 200 pounds within the line 131 to 180 pounds within the conduit 136. The pressure relief valve 142, which may be similar to that disclosed in Patent No. 2,055,465, application for which patent was filed by me, is

precautionary and should be set to pop off at 181 pounds in order to prevent pressure within the receiver 143 and the conduit 136 from building up further if the pressure regulator 135 should fail to function properly at any time.

The charger valve 147 and the bleeder timing valve 154 both will be opened slightly. The piston assembly is at the extreme left, as appears in Fig. 11. In this position, high pressure casing valve 113 is open and discharging pressure fluid into the annular space 1a through the high pressure supply line 131; while the valve 116, controlling the casing bleeder conduit 156, is closed. At the same time, the high pressure feeder valve 115 is open and discharging pressure fluid of the value of 200 pounds into the high pressure cylinder conduit 149 and the receiver 148 via the high pressure feeder conduit 146; while the high pressure bleeder valve 114, adapted to bleed pressure fluid out of the high pressure receiver 148 and the high pressure cylinder conduit 149, is closed.

Pressure fluid will build up to 180 pounds within the low pressure receiver 143 and the conduit 136 and stop building up at that pressure on account of the assumed twenty pounds reduction accomplished by means of the pressure regulator 135 while the pressure within the receiver 148 and the conduit 149 will continue building up to 190 pounds; whereupon the latch will be sprung and the piston assembly will move all the way to the right; thereby terminating the flowing operation.

At conclusion of the flowing operation, the high pressure casing valve 113 is closed and no more pressure fluid can enter the annular space 1a, the casing bleeder valve 116 being then open and bleeding the pressure fluid remaining within the annular space 1a to atmosphere through the casing bleeder conduit 156. At the same time, the high pressure bleeder valve 114 is open and wasting to atmosphere pressure fluid out of the receiver 148 and the conduit 149, while the high pressure feeder valve 115, adapted to charge that receiver and conduit, is closed.

Whenever the pressure within the high pressure receiver 148 and the high pressure cylinder conduit 149 is decreased to 170 pounds, as specified in the foregoing assumptions, the latch will be sprung again and the piston assembly will return to the left as shown in Fig. 11; whereupon the cycle as described, will repeat automatically while the high pressure supply line 131 remains charged with pressure fluid of proper value.

It will be observed that the pressure remains constant within the low pressure receiver 143, while the variation in pressures which actuates the piston assembly takes place in the high pressure receiver 148 and the conduit 149, due to the alternate charging and bleeding of that receiver by the needle valves 147 and 154.

It should be noted also that the latch should be adjusted to operate at somewhat less pressure than the difference in pressures resulting from the action of the pressure regulator. This regulator is employed in order that there always will exist such difference between the pressures obtaining in the opposing cylinders as will spring the latch safely and operate the piston assembly in its movements that actuate the four valves mounted upon the platform 110.

The duration of the flowing operation is controlled by the setting of the charger needle valve 147 which controls the time required to build up sufficient pressure within the high pressure re-

ceiver 148 and the high pressure cylinder conduit 149 to drive the piston assembly to the right.

The duration of the intervals between flowing operations is controlled by the setting of the bleeder valve 154, which controls the time required to reduce the pressure within the high pressure receiver 148 and the high pressure cylinder conduit 149, far enough below the constant pressure within the low pressure receiver 143 to spring the latch and to cause the piston assembly to return to the left, as shown in Fig. 11.

It should be noted also that the time required to build up pressure high enough within the high pressure receiver 148 and the high pressure cylinder conduit 149 to force the piston assembly to the right and terminate the flowing operation, is constant at any setting of the charger valve 147. In practice, this valve should be set so that the well will not pump off and blow through from bottom within the predetermined flowing time of each flowing operation; but if the well should pump off before conclusion of the flowing time, the pressure within the high pressure supply line 131 will decrease suddenly. Such decrease below the value of the assumed 180 pounds within the receiver 143 and the conduit 136 will open the check valve 145 and discharge pressure fluid out of the low pressure receiver 143, and the low pressure cylinder conduit 136 back into the line 131; thus quickly reducing the pressure within that receiver and conduit and almost instantly causing the piston assembly to move to the right; thereby terminating that particular flowing operation then, instead of allowing the high pressure casing valve 113 to remain open and to waste gas through the well while the charger valve 147 would build up pressure high enough within the high pressure receiver 148 and the high pressure cylinder conduit 149 to move the piston assembly to the right.

It is evident that a packer may be set between the tubing 2 and the casing 1, proximately above the lower end of the tubing, in combination with a check valve in the tubing, for the purpose of preventing pressure fluid within the annular space 1a from contacting the producing formations of the well.

Obviously, many minor changes in construction and arrangement of parts, as well as the substitution of mechanical equivalents for parts shown, may be made within the scope and purpose of the stated objects and appended claims, and I reserve the right to make such changes, arrangements, and substitutions.

I claim:

1. In an intermitter for an oil well having a casing and tubing concentrically arranged to provide a closed annular space for pressure fluid, and a high pressure supply line proximate to said well: an outward extension on said tubing; a platform secured upon said outward extension; a valve assembly comprising a high pressure casing input valve, a casing bleeder valve, a first feeder valve, a first bleeder valve, a second feeder valve, and a second bleeder valve, each of said valves being mounted on said platform, the feeder valves and the bleeder valves being arranged in pairs so that one valve of each pair opens while the other valve of that pair closes; an operating lever for each of said valves with each operating lever formed with a slot; a cylinder in spaced relation to said platform and valves, said cylinder having right and left ends; a piston member within said cylinder; drive pins upon said piston, each of said pins being slidable in one of said slots; each of said

right and left hand ends of said cylinder being formed with a dashpot, and complemental structure on the corresponding end of said piston; a latch upon said cylinder, said latch being adapted to delay and make sudden the movements of said piston; an operative connection between said latch and said piston; a lubricator reservoir operatively connected with said right end; a lubricator reservoir operatively connected with said left end; a lubricant in said reservoirs; a first and a second receiver proximate said well; a first conduit between said first receiver and said right lubricator reservoir; a second conduit between said second receiver and said left lubricator reservoir; a casing feeder conduit between said pressure supply line and said annular space, the first said valve being in said feeder conduit; a casing bleeder conduit between said annular space and said casing bleeder valve; a first feeder conduit between said pressure supply line and said first conduit, said conduit having said first feeder valve and a first charger timing valve therein; a first bleeder conduit between said first conduit and said first bleeder valve, said conduit having a first bleeder timing valve therein; a second feeder conduit between said pressure supply line and said second receiver, said conduit having said second feeder valve and a second charger timing valve therein; a second bleeder conduit between said second conduit and said second bleeder timing valve, said conduit having a second bleeder timing valve therein; an initial equalizing conduit connecting said first and second receivers, said conduit having valves therein; an emergency pressure relief conduit between said supply line and said first receiver; a check valve in said relief conduit; and a mechanical counter adapted to indicate the successive movements of said piston and valves.

2. In an intermitter for an oil well having a casing and tubing concentrically arranged to provide a closed annular space for pressure fluid, and a high pressure supply line proximate to said well: an outward extension on said tubing; a platform proximate said extension; a valve assembly comprising a high pressure casing input valve, a casing bleeder valve, a first feeder valve, a first bleeder timing valve, a second feeder valve, and a second bleeder timing valve, each of said valves being mounted on said platform, the feeder valves and the bleeder valves being arranged in pairs so that one valve of each pair opens while the other valve of that pair closes; an operating lever upon each of said valves; a cylinder in spaced relation to said platform and valves, said cylinder having right and left ends; a piston within said cylinder; drive pins upon said piston, each of said pins being adapted to move one of said operating levers; a latch proximate said cylinder, said latch being adapted to delay and make sudden the movements of said piston; an operative connection between said latch and said piston; a right lubricator reservoir operatively connected with said right end; a left lubricator reservoir operatively connected with said left end; a lubricant in said reservoirs; a first and a second receiver for pressure fluid proximate said well; a first conduit between said first receiver and said right lubricator reservoir; a second conduit between said second receiver and said left lubricator reservoir; a casing feeder conduit between said pressure supply line and said annular space, the first said valve being in said feeder conduit; a casing bleeder conduit between said annular space and said casing bleeder valve; a

first feeder conduit between said pressure supply line and said first conduit, said conduit having said first feeder valve and a first charger timing valve therein; a first bleeder conduit between said first conduit and said first bleeder valve, said conduit having a first bleeder timing valve therein; a second feeder conduit between said pressure supply line and said second receiver, said conduit having said second feeder valve and a second charger timing valve therein; a second bleeder conduit between said second conduit and said second bleeder valve, said conduit having a second bleeder timing valve therein; and means for accelerating the discharge of pressure fluid from said first receiver when the well blows through the tubing.

3. In a flow intermitter for an oil well having a casing enclosing a tubing to provide a closed annular space therebetween, and a high pressure supply line proximate to said well: an outward extension on said tubing; a valve assembly comprising a first feeder valve, a first bleeder valve, a second feeder valve, and a second bleeder valve, the feeder valves and the bleeder valves being arranged in pairs so that one valve of each pair opens while the other valve of that pair closes; a cylinder spaced from said valve assembly and having right and left ends; a piston within said cylinder; means upon said piston to operate said valves; a lubricator reservoir operatively connected with said right end; a lubricator reservoir operatively connected with said left end; a first and a second receiver proximate said well; a first conduit between said first receiver and said right lubricator reservoir; a second conduit between said second receiver and said left lubricator reservoir; a first feeder conduit between said pressure supply line and said first conduit, said conduit having said first feeder valve and a first charger timing valve therein; a first bleeder conduit between said first conduit and said first bleeder valve, said conduit having a first bleeder timing valve therein; a second feeder conduit between said pressure supply line and said second conduit, said conduit having said second feeder valve and a second charger timing valve therein; a second bleeder conduit between said second conduit and said second bleeder valve, said conduit having a second bleeder timing valve therein; and latching means operatively connected with said piston and cylinder for latching said piston.

4. In a flow intermitter for an oil well having a casing enclosing a tubing to provide an annular space therebetween, and a pressure fluid supply line proximate to said tubing: a valve assembly comprising a first feeder valve, a first bleeder valve, a second feeder valve, and a second bleeder valve, the feeder valves and the bleeder valves being arranged in pairs so that one valve of each pair opens while the other valve of that pair closes; a cylinder in spaced relation to said valves, said cylinder having right and left ends; a piston within said cylinder; means upon said piston to operate said valves; a first and a second receiver proximate said well; a first feeder conduit between said first receiver and said right end; a second conduit between said second receiver and said left end; a first feeder conduit between said pressure fluid supply line and said first conduit, said conduit having said first feeder valve and a first charger timing valve therein; a first bleeder conduit between said first conduit and said first bleeder valve, said conduit having a first bleeder timing valve therein; a second feeder conduit between said pressure fluid supply line and said second conduit, said conduit having said second feeder valve and a second charger timing valve therein; a second bleeder conduit between said second conduit and said second bleeder valve, said conduit having a second bleeder timing valve therein; and a second bleeder conduit between said second conduit and said second bleeder valve, said conduit having a second bleeder timing valve therein; and means for accelerating the discharge of pressure fluid from said first receiver when the well blows through the tubing.

between said pressure supply line and said second receiver, said conduit having said second feeder valve and a second charger timing valve therein; and a second bleeder conduit between said second conduit and said second bleeder valve, said conduit having a second bleeder timing valve therein.

5. In a flow intermitter for cased and tubed wells having an annular space between the casing and tubing: a cylinder; a piston within said cylinder; an assembly of six valves arranged in pairs and in spaced relation to said piston; means upon said piston and valves to open one of each said pair while closing the other of each said pair; a first pair of conduits having pressure fluid therein, said conduits being respectively connected to opposite ends of said cylinder; a second pair of conduits connected to one of said first pair of conduits and having pressure fluid therein; and a third pair of conduits connected to the other of said first pair of conduits and having pressure fluid therein; a fourth pair of conduits connected with said annular space, there being one of said valves in each of the aforesaid conduits, one conduit of said first pair of conduits being connected to one valve of a first of said pairs of valves and the other conduit of said first pair of conduits being connected to the other valve of said first pair of valves; one conduit of said second pair of conduits being connected to one valve of a second pair of said valves and the other conduit of said second pair of conduits being connected to a valve of the third pair of said valves; one conduit of the third pair of conduits being connected to the other valve of said second pair of valves and the other conduit of said third pair of conduits being connected to the other valve of said third pair of valves; by virtue of all of which pressure fluid will be alternately admitted to and discharged from said annular space and opposite ends of said cylinder.

6. In an intermitter for a well having a casing enclosing a tubing to provide an annular space about said tubing; a cylinder proximate said tubing; a piston within said cylinder; a casing bleeder valve connected with said annular space; a high pressure casing input valve connected with said annular space; a high pressure feeder valve connected with one end of said cylinder; a high pressure bleeder valve also connected with said one end of said cylinder; means for maintaining a predetermined pressure on the other end of said cylinder; means for lubricating said piston; and means to operate said valves by movements of said piston; by virtue of all of which the movements of the piston are timed to cause the well to flow intermittently.

7. In a flow intermitter for a well having a casing enclosing a tubing to provide an annular space therebetween, and a high pressure supply line proximate said well: an outward extension on said tubing; a platform upon said extension; a valve assembly on said platform comprising a high pressure casing input valve, a casing bleeder valve, a high pressure feeder valve, and a high pressure bleeder valve, said casing input valve and said casing bleeder valve constituting a pair of valves, and said high pressure feeder valve and said high pressure bleeder valve constituting another pair of valves, said valves being arranged so that one valve of each pair opens as the other valve of that pair closes; an operating lever upon each said valve; each of said operating levers being formed with a slot adapted to receive a drive pin; a cylinder in spaced relation to said

platform and valves, said cylinder having right and left ends; a piston within said cylinder; drive pins upon said piston, each of said pins being slidable in one of said slots; each of said right and left ends of said cylinder being formed with a dashpot, and complementary structure on the corresponding end of said piston; a latch upon said cylinder cooperatively connected with said piston, said latch being adapted to delay and make sudden the movements of said piston; a lubricator reservoir upon said right end; a lubricant in said reservoirs; a low pressure receiver proximate said well; a high pressure receiver proximate said well; a high pressure supply line communicating with said annular space, said line having said high pressure casing input valve in it; a casing bleeder conduit communicating with said annular space and connected to said casing bleeder valve; a low pressure cylinder conduit connected between said high pressure supply line and said low pressure receiver and right end lubricator reservoir; a pressure regulator and a check valve in said low pressure cylinder conduit; an emergency pressure relief conduit between said low pressure cylinder conduit and said high pressure supply line; a high pressure cylinder conduit between said high pressure receiver and said left lubricator reservoir and said left end lubricator reservoir; a high pressure feeder conduit between said high pressure line and said high pressure cylinder conduit, said high pressure feeder conduit having said high pressure feeder valve and a charger valve therein; a high pressure bleeder conduit between said high pressure cylinder conduit and said high pressure bleeder valve, said high pressure bleeder conduit having a bleeder timing valve therein; and a mechanical counter adapted to indicate the successive movements of said piston.

40 8. In a flow intermitter for a well having a casing enclosing a tubing to provide an annular space therebetween, and a high pressure supply line proximate said well: an outward extension on said tubing; a valve assembly comprising a high pressure casing input valve, a casing bleeder valve, a high pressure feeder valve, and a high pressure bleeder valve, said casing input valve and said casing bleeder valve constituting a pair of valves, and said high pressure feeder valve and said high pressure bleeder valve constituting another pair of valves, said valves being arranged so that one valve of each pair opens while the other valve of that pair closes; a cylinder in spaced relation to said valves, said piston having right and left ends; a piston within said cylinder; operative connections between said piston and said valves; a reservoir upon said right end; a reservoir upon said left end; a low pressure receiver proximate said well; a high pressure line communicating with said annular space, said line having said high pressure casing input valve in it; a casing bleeder conduit communicating with said annular space and connected to said casing bleeder valve; a low pressure cylinder conduit connected between said high pressure supply line and said low pressure receiver and right end reservoir; a pressure regulator in said low pressure cylinder conduit; a high pressure feeder conduit between said high pressure supply line and said left end reservoir and said high pressure receiver; a high pressure feeder conduit between said high pressure line and said high pressure cylinder conduit, said high pressure feeder conduit having said high pressure feeder valve and a charger valve therein; and a high pressure bleeder conduit

between said high pressure cylinder conduit and said high pressure bleeder valve, said high pressure bleeder conduit having a bleeder timing valve therein.

9. In an intermitter for an oil well having an eduction tubing and a casing around said tubing enclosing an annular space: means for supplying pressure fluid to said space to effect flowing of the well; means for controlling said pressure fluid to effect flowing operations at predetermined intervals of time; and means cooperating with said controlling means and with said pressure fluid supplying means for automatically affecting the operation of said controlling means thereby to terminate the flowing operations whenever the gas blows through from the bottom when the well cleans itself.

10. In an intermitter for an oil well having an eduction tubing surrounded by a casing enclosing

an annular space: means to supply pressure fluid to said space to effect flowing of the well; flow means including a cylinder and piston, and control flow control valves cooperatively connected

5 with said means to supply pressure fluid and connected with and operated by said piston; means including said valves for admitting pressure fluid to both ends of said cylinder and thereafter bleeding the pressure down from one end of the cylinder while simultaneously building up the pressure in the other end of the cylinder and vice versa during predetermined times to operate said valves so as to effect intermittent flowing of the well; and means cooperating with said controlling means and with said pressure fluid supplying means for automatically affecting the operation of said controlling means thereby to terminate the flowing operations when the well blows.

ALEXANDER BOYNTON.
